FILLING VALVE

Application filed December 15, 1924. Serial No. 755,856.

This invention relates to a filling machine and especially to a machine for filling cans, jars, bottles and the like with liquids, semi-liquids, etc.

5 Most filling machines in use today, and particularly those employed in fruit canneries for filling cans with syrup after fruit has been placed therein, are so designed that a portion of the filling valve enters the can or 10 other receptacle to be filled with syrup, the portion of the valve entering the can serving either the function of a displacement head or that of a venting member. In actual practice, this has proved to be rather a serious 15 objection as it has been found that any device entering the can has a tendency to cut or bruise the contents, this being particularly true when handling larger fruits, such as peaches, pears and the like.

20 The purpose of the present invention is to provide a filling valve which will eliminate cutting or bruising of the fruit. This is accomplished by so constructing the valve that the portion thereof which enters the can 25 either as a displacement member, vent or otherwise may be formed of rubber or any other resilient material which will yield or bend sufficiently if brought in contact with the fruit to prevent cutting or bruising 30 thereof.

One form which our invention may assume is exemplified in the following description and illustrated in the accompanying drawings, in which—

35 Fig. 1 is a central vertical longitudinal section of the filling valve forming the subject matter of the present application.

Fig. 2 is a similar view showing a modified form of sealing gasket.

40 Fig. 3 is a bottom view of the valve shown in Fig. 1.

Fig. 4 is a bottom view of the valve and sealing gasket shown in Fig. 2.

45 Fig. 5 is a detail cross-section showing a modified form of venting member.

Fig. 6 is an enlarged longitudinal section of one of the venting members shown in Fig. 1.

50 Referring to the drawings in detail, and particularly to Fig. 1, A indicates a main sup-

ply tank or reservoir in which is contained a suitable quantity of syrup such as indicated at 2. The filling valve B forming the subject matter of the present application is attached to the bottom of the tank shown at 3 and extends upwardly therethrough. The valve proper consists of a cylindrical base flange 4 extending through the bottom of the tank and secured thereto by means of screws 5 or other suitable means. Slidably mounted 55 in the base flange is a combined valve and venting member generally indicated at C. Extending upwardly from the base flange 4 are two or more interspaced vertical arms 6, and formed integral therewith and extending 60 radially inwardly are arms 7 which terminate in a central bearing member 8. A tubular extension 9 extends downwardly from the central bearing member and this tube, together with the central bearing 8, forms a 65 guide and a support for an adjustable venting member generally indicated at D, which will hereinafter be described.

The combined valve and venting member generally indicated at C consists of a cylindrical lower portion 10 which is vertically 75 slidable in the base flange 4. A packing gasket 11 is interposed between the same and a liquid-tight joint is in this manner maintained which will prevent escape or leakage 80 of liquid at this point. Formed on the lower end of the cylindrical portion 10 is an annular outwardly extending flange 12 and carried thereby is a combined sealing gasket and venting member generally indicated at E. This 85 gasket is circular. Its lower surface is provided with a plurality of downwardly projected tubular extensions 13. These extensions, together with the gasket proper, are cored out, as shown at 14, and these passages 90 align with venting tubes 15 carried by the cylindrical portion of the valve C. The venting tubes may be secured to the cylindrical portion or formed integral therewith as desired and they are so positioned that they will 95 extend upwardly between the arms 6 and 7, thereby permitting free vertical movement when the valve is in operation.

For the purpose of insuring registration between the venting passages 14 and the tubes 100

15, small tubular extensions 16 are vulcanized or otherwise secured to the upper surface of the sealing gasket E, and to prevent excessive flexibility of the tubular extensions 13 a fine helical spring 17 or the like may be placed in the rubber and vulcanized therein during the manufacture of the gasket, this being particularly illustrated in Fig. 6.

The gasket E serves three functions, first 10 that of sealing the upper end of the can F, second that of carrying the venting members or tubular extensions, and third the function of a valve. This last function is accomplished by forming an annular seat 18 in the inner 15 face of the gasket which is adapted to engage a stationary valve seat or disk 19 secured on the lower end of the stationary tube 9. The gasket E is normally held in contact with the valve disk 19 by means of a spring 20, this 20 spring surrounding the tube 9 and being interposed between the central bearing member 8 and a bearing disk 8^a which is secured to the lower cylindrical portion 10 of the member C by means of a plurality of radial arms 25 21. The spring, in other words, exerts a downward pressure on the member C and as such maintains the annular shoulder 18 of the gasket in contact with the outer periphery of the valve disk and the liquid flow between 30 the can and the container A is thus prevented when the valve is closed. The valve as a whole is otherwise provided with a liquid seal trap formed by the annular flanges indicated at 22 and 23. The flange 22 forms a 35 part of the cylindrical portion 10 of the member C and it extends downwardly. The flange 23 extends upwardly and is formed as a part of the valve disk 19. The two annular flanges form a tortuous passage through 40 which the liquid flows when the valve is opened, and they form a liquid seal trap to prevent further flow of liquid when a predetermined liquid level has been obtained in the can, as will hereinafter be described.

45 The operation of the valve will be as follows: It should first be understood that the tank A is preferably circular and that a number of filling valves are attached thereto. Mounted below the tank is a revolving table 50 to which the cans are delivered one by one. This table is provided with a series of plungers upon which the cans rest, and these plungers are elevated in successive order to force the cans upwardly against the sealing gasket 55 E, so as to seal the upper end of the can and also to lift the member C upwardly to open the valve and to permit the liquid to drain into the can. The revolving table, together with the plungers, the means for centering 60 the cans on the plungers, and the means for raising the plungers, is not here illustrated as practically all filling machines are provided with such mechanisms and therefore forms no part of the present application.

65 It should suffice to say that when a can is

brought into register with the filling valve, it is elevated a sufficient distance; first, to bring the upper edge in contact with the sealing gasket E, so that the upper end of the can will be sealed, and second to impart further upward movement of the can which is sufficient to move the member C upwardly against the tension of the spring 20. This upward movement raises the annular shoulder 18 of the gasket away from the valve plate 19 and in this manner opens the valve sufficiently to permit the liquid in the tank to drain downwardly through the tortuous passage formed by the annular flanges 22 and 23, and then to enter the can around the outer periphery of the valve disk. The liquid will continue to flow until the liquid level shown in Fig. 1 is reached. At this point the liquid reaches the lower ends of the venting members 13 and seals the same. Liquid will, however, continue to flow through the annular passage formed exteriorly of the valve disk 19 and the liquid entering, after the lower ends of the vents 13 have become sealed, will rise upwardly in the venting members until the same liquid level is attained as that in the tank A. During this upward rise of the liquid in the venting tubes 15, air is trapped between the valve disk 19 and the lower ends of the venting members 13. This air is gradually compressed as the liquid rises in the venting tubes and the final pressure attained will be equal to the hydrostatic head of the liquid in the tank and in the venting tubes. This hydrostatic pressure is, in other words, utilized to compress the air trapped between the valve plate 19 and the lower ends of the venting members 13 and the air thus compressed will serve the function of preventing further flow of liquid into the can when the final hydrostatic pressure is attained. This feature, however, forms no part of the present invention as it is fully illustrated, explained and claimed in our copending application entitled "Filling valve", filed March 19, 1923, Serial No. 626,110, but it is nevertheless referred to in this application so as to render the construction and operation of the valve as clear as possible.

When the final liquid level has been attained in the can, the plunger supporting the can recedes. The annular shoulder 18 is thus brought back into engagement with the outer periphery of the valve disk 19 and the can is further lowered with relation to the sealing gasket E to a point, where it may be removed during the step by step rotation of the table and plungers supporting the cans. The operation is repeated again and again as each can is brought into register with a filling valve.

Substantially all of the mechanism shown in this application is illustrated in our copending application referred to, the only new feature being that of providing the resilient

tubular venting members indicated at 13 and the central venting member D which will hereinafter be referred to. The provision of the resilient tubular venting members 13 is the most important feature of the present application. These members are sufficiently flexible to yield and bend as they enter the can, and particularly if they contact with the fruit placed therein. This yielding or bending prevents cutting and bruising of the fruit and it is this result which applicants desire.

The combined sealing gasket and venting member illustrated is provided with another feature which is also an improvement over the structure shown in our copending application. By referring to Fig. 3, it will be noted that a small rubber lug 25 is formed on the inner surface of the gasket in alignment with each venting member 13. These lugs serve the function of deflecting the inflowing liquid or splitting up the annular stream which would otherwise enter. The points of deflection take place in alignment with the venting members and thus break up the incoming stream of syrup or other liquid to such an extent that the air can freely escape through the inflowing stream of liquid as the can is being filled. For instance, if a complete annular stream of liquid were flowing over the outer periphery of the valve disk 19, the air in the center of the can could not escape to the vents 13, except by passing through the wall of the annular inflowing stream. This objectionable feature is overcome by splitting up the stream by means of the lugs 25 and perfect venting and escape of the air is insured.

The type of sealing gasket and vents shown in Fig. 1 is employed with practically all kinds of fruit except pineapples. Pineapples when canned are cut into flat disks such as shown at 27 in Fig. 2 and their center portions are cored out as at 28. The cans are substantially filled with these disks of pineapples and a venting member such as shown at 13 could not be employed as too great a space would be formed on the top of the can. In that instance the venting member D is employed and a sealing gasket such as shown at 29 is placed on the lower side of the annular flange 10. This gasket closes the venting tubes 15 and permits the venting member D to function.

The venting member D consists of a tube which passes through the central bearing member 8 and the extended tube portion 9 thereof. The upper portion of the tube is threaded as shown at 30 and it has a threaded engagement with the central bearing member 8. The balance of the venting tube is left smooth to serve the function of a packing surface and the lower end is closed by means of a disk 31. The tube is perforated as shown at 32 just above the disk and the lower face of the valve disk 19 is recessed to receive the disk

31. Hence, when the venting member D is not required, it is screwed upwardly until the disk 31 enters the recess in the lower end of the valve disk 19. The vents 32 are thus sealed and this part of the mechanism becomes inoperable. When the gasket E is removed and the substitute gasket 29 is applied, as shown in Fig. 2, the venting member D must be employed and it is brought into operation by merely turning the tube in a direction which will force it downwardly in the threads of the central bearing member 8. The venting member may be adjusted due to this threaded engagement, so as to attain any liquid level desired in the can, and it cannot injure the fruit, such as pineapple and the like, as it enters the can in the central core space 28, as indicated. Fig. 5 merely shows a modified form of gasket, such as employed in Fig. 1; that is a solid annular wall is formed on the lower face of the gasket as indicated at 34 and the venting passages are cored thereby as indicated at 35. This form of gasket is fairly suitable where large fruit is handled, such as peaches, pears and the like.

The reason for vulcanizing or placing a spring 17 in the tubular extension 13, as shown in Fig. 6, is to prevent excessive flexibility thereof, particularly in a vertical direction. Such a spring permits lateral deflection or bending movement, but it avoids vertical compression and to this extent may be desirable in many instances. Vertical compression or shortening of the venting member 13 to any extent would not be desirable as it would change the final liquid level in the different cans.

From the foregoing it can be seen that a filling valve has been provided which permits filling of the cans to a predetermined level without danger of cutting or bruising the fruit, this being accomplished by so constructing the valve that the portion thereof which enters the can may be formed of a flexible material, such as rubber or the like, and while the portion here illustrated serves the function of a venting member, it is obvious that a displacement head constructed of a resilient material could also be employed. We similarly wish it understood that the materials and finish of the several parts employed may be such as the experience and judgment of the manufacture may dictate or various uses may demand.

Having thus described our invention, what we claim and desire to secure by Letters Patent is—

1. In a filling device of the character described, a can closing and sealing gasket, and a plurality of flexible tubular venting members on the lower face of the gasket and insertible in the can when the gasket is applied, said venting members determining a final liquid level in the can.
2. In a device of the character described, an

- annular member forming a combination can closure and filling member, a valve cooperating therewith and forming an annular discharge opening into the can, a venting member and deflecting members adjacent the annular discharge opening adapted to divide the liquid into a number of separate streams to create a plurality of free air passages when filling the can.
3. In a device of the character described, an annular member forming a combination can closure and filling member, a valve cooperating therewith and forming an annular discharge opening into the can, a plurality of venting members carried by the annular member and insertible in the can when filling the same, and a deflecting member adjacent each vent and adapted to divide inflowing liquid into a number of separate streams when filling the can.
4. In a device of the character described, an annular member, a gasket carried thereby and forming a can closing and sealing device, a valve cooperating therewith and forming an annular discharge opening into the can through which the can may be filled with a liquid, a plurality of rubber tubes extending downwardly from the gasket and insertible in the can when the gasket is applied, said rubber tubes forming venting members which determine a final liquid level in the can, and a reinforcing member in each venting tube to prevent collapse thereof when engaging material within the can.
5. In a device of the character described, an annular member, a gasket carried thereby and forming a can closing and sealing device, a valve cooperating therewith and forming an annular discharge opening into the can through which the can may be filled with a liquid, a plurality of rubber tubes extending downwardly from the gasket and insertible in the can when the gasket is applied, said rubber tubes forming venting members, a deflecting member adjacent each vent and adapted to divide an inflowing stream of liquid into a number of separate streams when filling a can, and a spiral spring in each venting tube to prevent collapse thereof if bent or deflected by contact with material within the can.
6. In a device of the character described, an annular member, a gasket carried thereby and forming a can closing and sealing device, a valve cooperating with the gasket and forming an annular discharge opening into the can through which the can may be filled with a liquid, a plurality of rubber tubes formed on the lower face of the gasket and extending into the can when the gasket is applied, said rubber tubes forming venting members, a plurality of venting tubes carried by the sleeve-like member, and means insuring registration between the rubber venting tubes and the last-named venting members.

7. In a device of the character described, an annular member forming a combination can closing and filling member, a valve cooperating therewith and forming an annular discharge opening into the can through which liquid flows to fill the can, a centrally disposed venting tube, means permitting vertical adjustment of the same, and means for closing the venting tube when raising it to a predetermined position, said means opening the venting tube when it is lowered.

8. In a device of the character described, an annular member forming a combination can closing and filling member, a valve cooperating therewith and forming an annular discharge opening into the can through which liquid flows to fill the can, a movable venting tube, means permitting adjustment of said tube, and means for closing the venting tube when it is moved to a predetermined position, said means opening the venting tube when it is moved away from said position.

9. In a device of the character described, a can closing and sealing gasket, a flexible venting member on the lower face of the gasket and insertable in the can when the gasket is applied, said venting member determining a final liquid level in the can.

10. In a device of the character described, an annular member forming a combination can closure and filling member, a valve cooperating therewith and forming an annular discharge opening into the can, a venting member carried by the annular member and insertable in the can when filling the same, and a deflecting member adjacent the vent and adapted to divide the stream of inflowing liquid when filling the can.
